BY *Dexter Robb*
D.R. ATTORNEY'S

UNITED STATES PATENT OFFICE.

ROY HANMORE GERARD, OF BERKELEY, CALIFORNIA.

SIGN-HOLDER FOR TELEPHONE-DIALS.

1,000,794.

Specification of Letters Patent. Patented Aug. 15, 1911.

Application filed November 23, 1910. Serial No. 593,944.

To all whom it may concern:

Be it known that I, ROY HANMORE GERARD, a citizen of the United States, residing at Berkeley, in the county of Alameda and

5 State of California, have invented certain new and useful Improvements in Sign-Holders for Telephone-Dials, of which the following is a specification.

This invention consists of a novel attachment particularly designed for use in connection with automatic telephones of the type wherein a revolving dial is employed upon the subscriber's instrument, for making calls, and a finger stop associated with 15 the dial for limiting the movement of the latter in the customary manner.

At the present time the dial of the subscriber's telephone is provided with indicia, including directions for operating the instrument, and since the dial rotates and is brought to rest in any one of about eleven different positions, the above indicia is frequently up-side-down, and therefore inconvenient for reading by an operator unfamiliar with the use of the apparatus.

The present invention provides a holder for a sign, or the like and which is mounted upon the axis of the rotatable dial, but is held stationary by the finger stop so that 30 the directions upon the holder are always readable, and, furthermore, by reason of the location of the holder at the central portion of the dial, said directions are prominently placed, resulting in obvious 35 advantages.

For a full understanding of the invention reference is to be had to the following detail description and the accompanying drawings, in which—

40 Figure 1 is a view showing an ordinary automatic telephone and subscriber's set, of the desk type, and showing the invention in operative position with respect to the dial thereof; Fig. 2 is a transverse sectional view of the invention alone and operatively arranged with respect to the screw axis of 45 the dial; Fig. 3 is a combined plan and edge view of the sign holder; and Fig. 4 is a plan view of the sign which is preferably removably applied to the holder.

In the drawings, the numeral 1 designates the standard of an ordinary subscriber's desk set telephone and the numeral 2 the receiver supported thereon in the common 55 manner. As in the ordinary apparatus, the finger dial 3 is mounted rotatably upon the

base of the standard 1, being supported by a screw 4. Near its outer periphery the dial 3 has the finger openings 5 and the finger stop 6 associated with the dial projects over, 60 or overlaps, an edge portion of the dial so as to be engaged by the finger of an operator who rotates the latter part.

The sign holder comprising the present invention consists preferably of a circular body or plate 7 of a diameter somewhat less than the diameter of the space surrounded by the finger openings 5 of the dial 3, and said plate or body 7 is formed at its center with an upwardly flared opening 8 adapted 70 to receive the head of the screw 4 somewhat loosely so that the sign holder will not interfere with the free rotation of the dial 3, the latter being arranged beneath the sign holder when the same is properly applied 75 to the telephone. At a suitable point in its periphery, the body 7 of the sign holder is provided with a notch 9 receiving the inner extremity of the finger stop 6, the stop thus coöperating with the sign holder to prevent 80 rotation thereof, since the finger stop itself is stationary. A washer 10 may be interposed between the under side of the sign holder and the upper face of the dial 3.

If desired, the directions for using the 85 telephone may be printed, inscribed, pressed or otherwise formed upon the upper surface of the body 7 of the sign holder and said directions will always be readable by reason of the stationary mounting of this part. As 90 shown in the drawings, however, the plate from which the sign holder is made has its peripheral edge formed with an inwardly curved flange 7' adapted to overlap a detachable disk 11, made of paper or similar material and on which the directions for using the telephone are printed. To protect the disk 11, a cover disk 12 is preferably employed, the latter being made of any suitable transparent substance. The printed disk 11 95 may be formed with a projection 13 on its periphery.

When the sign holder is made in the manner shown in Fig. 3, the disk holding flange 7' is split and the split ends bent outwardly 105 as shown at 7'' to form grooved projections, and the space between the said projections constitutes the notch 9, before referred to. The disk 11 will be seated on the sign holding body 7 and positioned properly by interlocking the projection 13 between the projections 7''. The projections 7'' on the sign

holder snugly receive the inner extremity of the finger stop therebetween and thereby establishing the locking connection between the sign holder and the stop 3.

- 5 The sign holder may be made of any suitable material in carrying out the invention, and it is to be understood that the specific structure of the various parts as hereinbefore described may be modified, having in
10 view the special objects of the invention, and the scope of the claims hereto appended.

Having thus fully described my invention, what is claimed as new is:

1. In combination with a telephone set
15 embodying a rotatable finger dial and a finger stop associated therewith, and a sign holder supported by the axis of the dial and having interlocking connection with the finger stop whereby movement of the holder
20 is prevented during rotation of the dial.
2. In combination with a telephone set comprising a rotatable dial provided with finger openings adjacent to its peripheral portion, an axis for said dial passing through
25 the same, a sign holder arranged over the dial and of a diameter less than the space surrounded by the openings aforesaid, and a stationary finger stop associated with the dial and projecting over the edge portion of
30 the latter and interlocking with the edge portion of the sign holder.
3. In combination with a telephone set

embodying a finger dial, a headed screw passing through said dial and constituting the axis thereof, a finger stop associated 35 with the dial and extending over the edge portion of the latter toward its center, and a sign holder through which the screw aforesaid passes, said sign holder being arranged above the dial and having a peripheral notch 40 receiving the inner extremity of the finger stop, whereby the sign holder is prevented from rotation during the movement of the dial.

4. As a new article of manufacture, a sign 45 holder for automatic telephone sets comprising a centrally apertured plate of substantially circular form, the edge portion of the plate being formed with a sign holding flange, said flange being split at a suitable 50 point and the split ends being bent outwardly so as to provide spaced projections, and a sign comprising a disk held in place on the holder by the edge flange aforesaid, said sign having a peripheral projection extending into the space between the spaced 55 projections of the holder.

In testimony whereof I affix my signature in presence of two witnesses.

ROY HANMORE GERARD.
